(57) **CLAIM**

The ornamental design for a scraper blade for a conveyor belt cleaner, as shown and described.

DESCRIPTION

FIG. 1 is a perspective view of a scraper blade for a conveyor belt cleaner;

FIG. 2 is a top plan view of the scraper blade;

FIG. 3 is a front elevational view of the scraper blade;

FIG. 4 is a bottom view of the scraper blade;

FIG. 5 is a left side elevational view of the scraper blade, the right side elevational view being a mirror image; and,

FIG. 6 is a rear elevational view of the scraper blade.
